UNITED STATES PATENT OFFICE.

ROBERT B. CASWELL, JR., OF BALTIMORE, MARYLAND.

CALKING VESSELS.

SPECIFICATION forming part of Letters Patent No. 430,375, dated June 17, 1890.

Application filed April 22, 1890. Serial No. 349,048. (No model.)

To all whom it may concern:

Be it known that I, ROBERT B. CASWELL, Jr., a citizen of the United States, residing at Baltimore, in the State of Maryland, have invented certain new and useful Improvements in Calking Vessels, of which the following is a specification.

This invention relates to a new and useful improvement for filling the seams between the planks of vessels or planks used for any other purpose, so as to make said seams water-tight. The ordinary term for this operation is "calking."

The drawings illustrate the invention.

Figures 1 and 2 show a seam between two planks calked according to my invention. Figs. 3, 4, and 5 show seams illustrating a modification of the calking.

The improvement may be used with or without oakum. The drawings illustrate both ways.

In Figs. 1 and 2 oakum *a* is first driven, as usual, in the seam *b* between the planks *c*. In doing this space must be left in the seam on top of the oakum for the lead filling *d*, which is the feature of my invention. I use sheet-lead strips *d*, which are broad enough to fold longitudinally along both edges, as indicated at *f*. A strip of this folded sheet-lead is then driven in the prepared seam by a calking-iron and mallet or beetle. The soft lead under the action of the calking-iron spreads and wedges in the seam very tight, and forms in cross-section a sort of lead dovetail in the

seam. The lead confines the oakum, and the secure hold of the lead on the wood makes a 35 permanently-tight seam.

The sheet-lead may be used alone without oakum, as in Figs. 3 and 4. In this case the seam is first opened, as usual, by a reaming-iron, and after this preparation of the seam 40 the strip of sheet-lead is forced in, as already described.

The herein-described calking for seams and the method of filling the seams, considered as an invention, are interdependent, or have 45 such necessary relation as to constitute a unitary invention. I therefore make claim to both.

Having described my invention, I claim—

1. The herein-described improvement in 50 calking, consisting in the use of strips of lead driven in the seam between planks to form therein a wedge or dovetail.

2. The method of calking seams, consisting of preparing or opening the seam as usual, 55 then placing sheet-lead strips folded longitudinally along the seam, and driving the same into the seam with suitable tools until the lead forms a wedge or dovetail.

In testimony whereof I affix my signature in 60 the presence of two witnesses.

ROBERT B. CASWELL, JR.
